EYEGLASS CONSTRUCTION

George E. Nerney, Attleboro, Mass., assignor to
 Bay State Optical Company, Attleboro, Mass.,
 a corporation of Maine

Application June 19, 1940, Serial No. 341,286

2 Claims. (Cl. 88—49)

This invention relates to eyeglass construction and more particularly to the mounting of nosepads.

One of the objects of this invention is to provide a nosepad mounting which will be especially strong in spots which are normally vulnerable in the usual type of the above construction. Another object is to provide a construction of the above character which is simple, thoroughly practical, and durable. Another object is to provide a construction of the above character which may be manufactured economically, both from the standpoint of labor and materials used. A further object is to provide a construction of the above character which permits a nosepad mounting to be easily and quickly adjusted. A still further object is to provide a construction of the above character which provides portions which may be securely and easily gripped by tools during adjustment of a nosepad mounting. Other objects will be in part obvious and in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawing in which is shown one of the various possible embodiments of my invention,

Figure 1 is a fragmentary front elevation of a portion of a pair of eyeglasses in position upon the nose of a wearer;

Figure 2 is a horizontal section taken on the line 2—2 of Figure 1;

Figure 3 is a prospective view on an enlarged scale of the nosepad and nosepad mounting arm shown in Figures 1 and 2;

Figure 4 is a rear elevation of the nosepad construction shown in Figure 3;

Figure 5 is a top plan view of the nosepad construction shown in Figure 3; and

Figure 6 is a side elevation of the construction shown in Figure 3.

Similar reference characters refer to similar parts throughout the several views of the drawing.

As conducive to a clearer understanding of certain features of this invention, it might here be pointed out that mounting the noseguards for eyeglass frames has presented many problems in the past. In practice, it has been found that in order to support the central portion of an eyeglass frame properly upon the nose of

the wearer, noseguards should contact the sides of the nose firmly. Thus, each nosepad is adjusted to accurately fit the face of the wearer, and the surface upon which the nosepad rests varies in three directions—namely, vertically, horizontally, and diagonally therebetween. In the past, difficulty has been experienced in making a nosepad mounting which may be easily and properly adjusted to allow for these variations. 10 A further difficulty lies in the fact that it is difficult for the retailer to obtain a secure grip with his tools upon the nosepad mounting in making the necessary adjustments. Furthermore, such failure to obtain a proper grip often results in excessive strains being placed upon portions of the nosepad or mounting therefore, with resultant damage thereto. Accordingly, it is another object of this invention to provide a nosepad mounting adapted to overcome the above mentioned difficulties, as well as many others.

It might here be noted that reference hereinafter to an "outward" direction signifies a direction to the right or the left of the center of the bridge of an eyeglass frame in the direction of the temple, while the term "inward" denotes a direction toward the center of the bridge from one of the temples. A "rearward" direction refers to a direction toward the face of a wearer, whereas the term "forward" denotes the opposite direction thereto. An "upward" direction refers to a direction upwardly from the face of a wearer, while a "downward" direction is opposite thereto.

Referring now to the drawing in detail, there is shown in Figures 1 and 2 the bridge portion of an eyeglass frame, including a bridge 10 secured to a pair of rims 11 and 12 which mount lenses 13 and 14. Extending rearwardly from each of the connecting points between rims 11 and 12 and bridge 10 is a noseguard mounting arm. These arms, generally indicated at 15 and 16, carry nosepads 17 and 18 respectively. As nosepad mounting arms 15 and 16 are substantially similar in construction, being merely of reversed configuration so that they can provide support on the right and left side of a face, the description hereinbelow is limited to arm 15 which supports nosepad 17.

As best shown in Figures 3 and 6, arm 15 has one end 19 secured to rim 11 and the other end 20 secured to nosepad 17 and the arm includes three sections—namely, a rearwardly extending section 21, a downwardly extending section 22, and a forwardly extending section 23. The rearwardly extending section 21 has a substantially

straight portion which extends rearwardly from its point of connection to the rim substantially to the edge of the upper end of nosepad 17 (Figure 5). At this point section 21 curves outwardly and thence follows a semi-circular path terminating at a point which lies adjacent the rearward edge of the upper portion of the nosepad. As shown best in Figures 5 and 6, all portions of this section lie in a substantially flat horizontal plane, so that it may be securely gripped by a pair of pliers, as will be more fully described hereinafter.

Referring now to Figures 4 and 6, section 22 extends downwardly from the rearwardly extending section 21 at substantially a right angle thereto and follows the outer surface of the nosepad adjacent the edge thereof, terminating at a point adjacent the edge of the center portion of the nosepad. Section 23 connects to the downwardly extending section 22 at this point and extends forwardly across the center of the nosepad terminating adjacent the forward edge thereof.

The nosepad is connected to the last mentioned section by means of the connection disclosed in the United States Patent to Person, No. 2,209,827, which issued July 30, 1940. An open-ended box-shaped member 25 is mounted transversely on the nosepad and is adapted to receive the end of section 23 which is reduced in size as indicated by the dotted line 60 (Figure 5). A tongue 28 on member 25 is bent into a notch on the end of section 23 connecting the nosepad to the arm. This securely mounts the nosepad on arm 15, and due to the fact that the arm is slightly smaller than the opening extending through box-shaped member 25, limited rocking motion is permitted between the arm and the nosepad.

Referring now to Figure 4, it may be seen that this nosepad mounting is so constructed that adjustments of the nosepad may be easily and quickly made. In order to make vertical adjustments or those adjustments necessary to fit the nosepad to the vertical shape of a face, the rearwardly extending section 21 is grasped between the jaws 31 (Figure 4) of a pair of pliers. The curved portion of this section assures a firm grip thereon and prevents it from rotating between the jaws while adjustments are being made. The nosepad, section 22 and section 23 are then gripped between the jaws 30 of another pair of pliers. A secure grip is assured as sections 22 and 23 and member 25 lie in a single plane parallel to the flat surface of the nosepad and are all of substantially the same thickness. The vertical adjustment of the nosepad may then be varied by bending the arm 15 at point 24 to the right or the left of the nosepad as viewed in Figure 4. As sections 23 and 24 are both positioned adjacent the rear surface of nosepad 17, the pliers secure a firm grip on these sections of the arm and the nosepad. This effectively prevents injurious strains from being placed on the connection between the nosepad 17 and the arm 15.

In making adjustments to fit the nosepad to the curved surface 33 (Figure 2) which extends between the nose and the eye of the wearer, the pliers are used in the same positions. In this type of adjustment the shape of section 21 also affords a secure grip on this portion of arm 15. To make the adjustment, the pliers having jaws 30 are twisted so that the nosepad rotates with section 22 as a center. By this action proper horizontal adjustments may be attained, and as

the jaws 30 extend across section 23, this section acts as a lever on section 22 to twist it into the proper position with respect to section 21. Diagonal adjustments are also made with the pliers in the positions shown in Figure 4, and arm 22 is bent about point 24 to the right and left of the position shown in Figure 6. As in vertical adjustment, the positioning of the pliers and the design of the sections prevent damage to the connection between the nosepad and the arm during these last two adjustments.

Thus all of the required adjustments may be easily and quickly made by the retailer. Furthermore, the arm has been so designed that the pliers may secure a firm grip thereon to make these adjustments without fear of damage to the connection between the nosepad and the mounting arm.

Accordingly, it will be seen that I have provided an efficient and thoroughly practical construction, in which the several objects hereinabove set forth, in addition to many others, have been successfully accomplished.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

I claim:

1. In eyeglass construction, in combination, an eyeglass frame, a nosepad, a nosepad arm secured to said frame, said nosepad arm including rearwardly, downwardly, and forwardly extending sections, said rearwardly extending section extending rearwardly to the forward edge of said nosepad and then following a semi-circular path to the rear edge of said nosepad, said downwardly extending section extending downwardly adjacent the rear edge along one side of said nosepad so that its inner surface is juxtaposed to one of the substantially flat surfaces of said nosepad, and said forwardly extending section extending forwardly substantially across the side of said nosepad, said downwardly and forwardly extending sections lying in a single plane, and means connecting said nosepad to said forwardly extending section.

2. In eyeglass construction, in combination, an eyeglass frame, a nosepad, a nosepad arm secured to said frame, said nosepad arm including rearwardly, downwardly, and forwardly extending sections, said rearwardly extending section

lying in a single plane which has a curved portion therein permitting a secure grip to be obtained upon this section during adjustment, said downwardly extending section extending downwardly from the rear end of said rearwardly extending section adjacent the rear edge of and following the side of said nosepad so that its inner surface is juxtaposed to one of the substantially flat surfaces of said nosepad, and said forwardly extending section extending forwardly

from the lower end of said downwardly extending section across the side of said nosepad, an open-ended box-shaped member mounted on and extending transversely of said nosepad, said box-shaped member being adapted to receive a portion of said forwardly extending section, and means to secure said forwardly extending section within said box-shaped member.
